CLAIM

The ornamental design for a handle for a portable bag closing sewing machine, as shown.

DESCRIPTION

FIG. 1 is a perspective view of the handle for a portable bag closing sewing machine showing our new design; FIG. 2 is a top plan view thereof;

FIG. 3 is a bottom plan view thereof;

FIG. 4 is a left side elevational view thereof;

FIG. 5 is a front elevational view thereof;

FIG. 6 is a rear elevational view thereof; and

FIG. 7 is a right side elevational view thereof.
